UNITED STATES PATENT OFFICE

MELVILLE H. BARKER, OF BOSTON, MASSACHUSETTS.

SUPPORTING AND DRIVING MEANS FOR CENTRIFUGAL MACHINES.

1,103,341.

Specification of Letters Patent. Patented July 14, 1914.

Application filed February 23, 1904. Serial No. 194,653.

To all whom it may concern:

Be it known that I, MELVILLE H. BARKER, a citizen of the United States, and resident of Boston, county of Suffolk, Massachusetts, have invented certain new and useful Improvements in Supporting and Driving Means for Centrifugal Machines, of which the following is a specification.

This invention relates to centrifugal machines and has for its object the general improvement of this class of machines in respect to their efficiency and durability. Heretofore suspended machines of this type have employed in some cases a single solid 10 rotary shaft to which the basket is secured, and in other cases a central supporting spindle upon which is carried a hollow rotary basket shaft, the former construction being simpler and cheaper while the other is more 15 efficient and better adapted to the highest speeds and greatest weight of load.

One of the principal problems in connection with centrifugal machines to-day, relates to the suspension and driving of such 20 machines in a manner to avoid objectionable heating of the bearings and one of the special objects of the present invention is to provide a construction by which the supporting bearings are so arranged as to secure 25 practically perfect lubrication and to avoid undue stress or strain upon the bearings whereby the before mentioned difficulties may be easily avoided.

To this end my invention comprises a construction and arrangement by which I am 30 enabled to use a single rotary supporting spindle or shaft while securing all the advantages of the double spindle type of machine, the outside hollow shaft being entirely dispensed with.

Other features characterizing my invention will be explained in this specification and will be particularly pointed out in the claims forming part thereof.

In the drawings Figure 1 is a central vertical section of the principal parts of a centrifugal machine showing my method of direct connection with an electric motor. Fig. 2 is a side elevation of the same, viewed 45 at right angles to the plane of Fig. 1. Fig. 3 is a plan view of the machine. Fig. 4 is a detail showing in section the suspension arms which carry the field of the motor.

In the practice of my invention according to the embodiment illustrated in the drawings, I provide a fixed supporting

hanger *a*, which is of approximately U-shape, being open on opposite sides for a purpose to be hereafter explained, and being provided with a spherical bearing socket 60 *a'*. This hanger is rigidly supported by girders or any means for rigidly holding the same at a suitable distance above the floor. I also provide a hollow oscillatory suspension or sleeve member *b* which is 65 formed with a spherical bearing surface or ball *b'* adapted to seat in the socket *a'* to afford free oscillation on every side of the central axis. As herein shown this oscillatory sleeve member is constructed with an 70 outside wall *b*² and an inside wall or flange *b*³, thus leaving a hollow annular space which serves as an oil reservoir or well. The bottom of this reservoir is provided with a suitable bearing face upon which is 75 supported a rotating head *c* to which is keyed or otherwise fastened the basket-carrying shaft *d*. It will be noticed that the head *c* is provided with a cylindrical bearing surface fitting close against the outer face of 80 the flange or wall *b*³ thus forming a lateral bearing to prevent any sidewise play or movement and also to prevent the drawing up of oil over the top of the flange *b*³ which would be objectionable because in such case it 85 would run down upon the armature or drip into the basket and spoil the contents thereof. I have shown a series of bearing balls arranged between the bearing faces of the bearing head *c* and the oscillatory sleeve 90 member *b*.

As shown the shaft *d* is extended upward above the bearing head and passes through the hollow oil casing or cap *b*⁴ which is detachably secured to the top of 95 the oscillatory sleeve member *b* so as to form a cover for the oil well and to form an additional lateral bearing for the shaft. As this cap *b*⁴ is secured to the sleeve member *b* it must of course participate in its oscillatory movement. This cap is shown formed with an annular oil well whose inner wall or flange is provided with a vertical slot to receive a packing wick *d'* which distributes the oil upon the shaft at this point sufficiently to keep it lubricated. Any drip caused by leakage of this bearing packing will fall into the oil channel beneath and is thus prevented from running down the shaft to the armature or basket.

In order to afford a yielding resistance to the oscillatory movement of the shaft and

its suspension sleeve, I have provided an elastic gasket or buffer of rubber or other suitable material as shown at *e*. This is carried by an upwardly projecting portion of 5 the supporting bracket *a* and resists the oscillatory movement of the shaft by the resistance which it affords to the outer wall of the bearing cap *b*⁴. Of course any suitable means for affording a yielding resistance 10 may be employed and is preferably located above the plane of the supporting bearing face of the bearing head *c*. The rotary shaft or spindle *d* is continued down and is secured to the basket *f* in any suitable 15 or well known manner. I have not shown the outer casing which is employed with this class of machines because it being entirely independent of and unsupported by any other parts of the construction, such showing 20 is deemed superfluous.

Where it is desired to drive the machine by a direct connected electric motor, as shown in this case, I provide the oscillatory hanger *b* with projecting arms *b*⁵ which extend through the open sides of the supporting bracket *a* and to which is secured the non-rotatable field-magnet *X* of the electric motor, the rotating armature *Y* of said motor being secured directly to and supported 25 by the rotary shaft *d*. By this arrangement the only additional load put upon the rotary shaft is the weight of the armature itself, since the heavy field of the magnet is sustained entirely by the oscillatory hanger. 30 This relieves, to a considerable extent, the strain upon the rotary bearing surfaces upon which the weight of the shaft is sustained. The rotation of the oscillatory sleeve member is prevented by means of elastic buffers 35 *a*³ carried by suitable brackets or projections *a*⁴ formed on the supporting hanger *a* and arranged to engage the opposite sides of the supporting arms or extensions *b*⁶, these buffers *a*³ being preferably formed of blocks of 40 vulcanized rubber. The supporting arms *b*⁵ are provided with supporting heads *b*⁷ to which are detachably secured the two halves of the field-magnet by means of bolts *b*⁸. By this construction and arrangement 45 the removal of the bolts *b*⁸ permits the taking off of the field of the motor to give free access to the armature without disassembling other parts of the machine.

In order to stop the rotation of the machine 55 when the power is turned off, I have provided a novel form of brake mechanism which comprises a concave member *g* and a convex member *g'* provided with opposing coöperating friction surfaces, one of these 60 members, *g* for example, being keyed directly to the shaft *d*, while the other member is supported to slide vertically in order to be brought into gripping engagement with its coöperating rotatable member. In this 65 case the convex brake member *g'* is mounted

upon supporting pins or rods *g*² which slide in vertical bearings formed in the frame of the supporting hanger and which are raised and lowered by any suitable mechanism, such as an oscillatory yoke *g*³ provided with 70 a projecting arm *g*⁴ operated by a draft rod *g*⁵ through the medium of a screw *g*⁶ and hand wheel *g*⁷.

The above described arrangement enables the operator to easily apply the desired 75 amount of power for stopping the machine and locking it against movement after it is stopped. The coöperating friction surfaces of the brake members *g*, *g'* are preferably struck substantially from the center of oscillation of the shaft so that their relationship may not be disturbed by such oscillatory movements.

It will be seen that with the construction 80 of apparatus above described I am able to use a direct connected motor for driving the machine while adding the minimum amount of load to be carried by the bearings and at the same time secure the perfect distribution of weight over a large bearing surface supported by ball bearings which run continuously in the oil so that the possibility of heating the bearings even under the heaviest loads is reduced to a minimum. I therefore 85 secure all the advantages possible with the solid spindle rotary sleeve suspension while employing the single rotary shaft construction. At the same time all possibility of the dripping of oil upon the armature or into the basket is completely avoided while I 90 secure a highly efficient and wellnigh frictionless rotary bearing for the basket shaft.

What I claim is—

1. A mount for centrifugal machines embracing in combination a solid rotary basket-carrying shaft, an oscillatory sleeve member 105 forming a means for suspending said shaft and having a thrust bearing and a lateral bearing for operatively sustaining said shaft in its rotation, a driving motor operatively connected to said shaft below its center of 110 oscillation the stator element of said motor being rigidly secured to and supported by the oscillatory sleeve, substantially as described.

2. A mount for centrifugal machines embracing in combination a supporting hanger, a sleeve member having an oscillatory bearing in said hanger, a rotatable basket-carrying shaft extending through said sleeve member and having rotary bearing support 120 on said sleeve member, a downwardly projecting yoke for rigidly securing a motor element to said sleeve member, and means for preventing the rotation of the sleeve 125 member, substantially as described.

3. A mount for centrifugal machines embracing in combination a fixed socketed hanger, an oscillatory sleeve member seated therein, an elastic buffer interposed between 130

5 said sleeve member and the hanger for yieldingly centralizing said sleeve member, a rotary basket-carrying shaft suspended through the sleeve member upon a thrust bearing located on said sleeve member, a driving motor located below the center of oscillation the elements of which are rigidly connected to the basket shaft and to the sleeve member respectively, substantially as 10 described.

4. The combination of the suspended oscillatory rotary solid basket shaft, the basket secured to the lower end thereof, an oscillatory non-rotating sleeve member 15 through which said basket shaft passes, said sleeve member being formed with both lateral and thrust bearing surfaces for the suspension of the rotary shaft and for maintaining axial alinement between the shaft 20 and the sleeve member, a motor whose rotor is secured to the basket shaft below the sleeve and whose stator is rigidly suspended from the sleeve itself, substantially as described.

5. A mount for a centrifugal machine 25 embracing in combination a fixed hanger, an oscillatory sleeve member seated therein, a rotary basket shaft suspended from a thrust bearing on the sleeve member said member being upwardly extended to form an oil reservoir inclosing the thrust bearing to keep said bearing immersed in oil, an encircling buffer interposed between the upward extension of the sleeve member and the surrounding portion of the hanger and a motor whose 30 35 rotor element is connected with the shaft to drive the same, substantially as described.

6. A mount for centrifugal machines embracing in combination a socketed hanger, an oscillatory sleeve member provided with an 40 external ball adapted to be seated in said socket, said sleeve member being also formed

with an interior oil reservoir, an anti-friction thrust bearing mounted in said oil reservoir, a rotary basket shaft suspended through the sleeve member and rotatably 45 supported upon said thrust bearing, a centralizing buffer encircling the sleeve member and a driving motor whose rotor element is connected with said shaft to rotate the same and whose stator element is rigidly suspended 50 from said sleeve member, substantially as described.

7. A mount for centrifugal machines embracing in combination a fixed hanger, an oscillatory sleeve member seated therein, a solid rotary basket shaft suspended upon said sleeve member by a thrust bearing located on the sleeve member, a driving motor whose elements are rigidly secured respectively to the sleeve member and to the shaft 60 in a plane below the sleeve member and a brake mechanism operatively connected with the upper end of the shaft above the sleeve member, substantially as described.

8. The combination of the solid oscillatory 65 rotary basket shaft, an oscillatory sleeve member from which said shaft is suspended, a direct connected driving motor located below the sleeve member, and an anti-friction brake located above the sleeve member and a centralizing buffer surrounding and engaging the sleeve member at a level between 70 the center of oscillation and the brake, substantially as described.

In witness whereof, I have hereunto set 75 my hand, this eighth day of February, 1904.

MELVILLE H. BARKER.
